Primary Examiner — Brett Miller(74) *Attorney, Agent, or Firm* — Cantor Colburn LLP(57) **CLAIM**

The ornamental design for a television receiver, as shown and described.

DESCRIPTION

FIG. 1 is a front perspective view of a television receiver, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the portion 9 in FIG. 1; and, FIG. 10 is an enlarged view of the portion 10 in FIG. 2.

The even-dash broken lines immediately adjacent the shaded areas represent the bounds of the claimed design while all other even-dash broken lines are directed to environment and are for illustrative purposes only; the even-dash broken lines form no part of the claimed design.
